UNITED STATES PATENT OFFICE.

GEORGE I. ROCKWOOD, OF WORCESTER, MASSACHUSETTS.

APPARATUS FOR OPERATING ALARMS OR OTHER DEVICES.

1,116,328.

Specification of Letters Patent.

Patented Nov. 3, 1914.

Application filed March 12, 1910. Serial No. 548,862.

To all whom it may concern:

Be it known that I, GEORGE I. Rockwood, a citizen of the United States, residing at Worcester, in the county of Worcester and 5 Commonwealth of Massachusetts, have invented a new and useful Improvement in Apparatus for Operating Alarms or other Devices, of which the following, with the accompanying drawings, is a specification.

10 My present invention relates to an alarm operating device designed to be used in connection with an automatic fire sprinkler system in which a device for producing an audible alarm is provided, designed to be 15 operated whenever a continuous passage of a liquid under pressure occurs through a pipe supplying the sprinkler heads, said alarm, however, remaining ineffectual during short intermittent passages of water through the 20 supply pipe, such for example, as those produced by what are known as water hammers.

It is the object of my present invention to render the operation of the alarm apparatus certain whenever a slight difference in 25 pressure occurs in the supply pipe, such, for example, as would result by the release of a single sprinkler head, and I accomplish this object by the construction and arrangement 30 of parts as hereinafter described and illustrated in the accompanying drawings, in which—

Figure 1 is a side elevation of an alarm controlling device embodying my present invention, the same being shown in central, vertical, sectional view. Fig. 2 is a view of the diaphragm supporting frame formed upon the side of and preferably integral with the water supply pipe.

40 Similar reference characters refer to similar parts in both figures.

Referring to the accompanying drawings 1 denotes a chamber having an inlet pipe 2, communicating with a water supply pipe 3 leading to a source of water supply under pressure. Upon one side of the supply pipe 3 is a circular opening 4 surrounded by a flange 5 and intersected by a spider, consisting of the radial arms 6, 7, 8 and 9. Secured 45 to the flange 5 by bolts is a cover 11. Between the cover 11 and the radial arms 6, 7, 8 and 9 is inclosed a space which is divided

55 by a flexible diaphragm 12, having its edges clamped between the flange 5 and the cover 11, forming between the diaphragm 12 and cover 11 an inclosed chamber 13. The chamber 13 communicates through an opening 14 in the cover and a pipe 15 with an annular space 16 inclosed between a section 17 of the water supply pipe and the smaller end of a 60 tapering pipe 18.

The larger end of the tapering pipe 18 is clamped between the flanged end of the section 17 and the flanged end of the supply pipe 3, so that the tapering pipe 18 will 65 form a continuation of the supply pipe 3. Between the section 17 and the pipe 19, upon which a sprinkler head 20 is mounted, I insert a tapering pipe 21, but tapered in the reverse direction from the pipe 18, with the 70 smaller end of the pipe 21 in alignment with the smaller end of the pipe 18. A narrow space 22 is provided between the smaller end of the pipe 21 and the smaller end of the pipe 18 to form a water communication 75 between the interior of said pipes and the annular space 16. The radial arm 9 of the spider is hollow to provide a water passage 23, the inner end of which is provided with a short nipple 24 which projects slightly 80 above the surface of the spider and forms a seat for the flexible diaphragm 12 when the latter is forced inward by water pressure in the chamber 13. The outer end of the water passage 23 receives the end of the pipe 2, 85 forming a communication between the chamber 1 and the interior of the supply pipe 3, except when it is closed by the flexible diaphragm 12.

When the system is filled with water the 90 static pressure, for equal areas, will be the same upon opposite sides of the diaphragm 12, but as the exposed area of the diaphragm upon the side next the chamber 13 is slightly greater than that upon the opposite side of the diaphragm, the latter will be forced 95 against its seat 24, thereby closing the passage 23 to the chamber 1. Should a movement of water occur upward through the tapering pipe 18 the lateral pressure of the 100 water at the smaller end of the pipe and at the opening 22 would be slightly lessened by a well known principle of hydraulics, thereby producing a slight reduction of pres-

sure in the annular space 16 and a corresponding reduction in the chamber 13. A slight difference in pressure thus produced upon the opposite sides of the diaphragm 12 5 will cause the latter to be lifted from its seat 24, allowing the water to flow through the pipe 2 into the chamber 1. Whenever the chamber 1 becomes filled a diaphragm 25 is forced upward, carrying with it the 10 attached tapered plug 26 which closes an opening 27 between an upper chamber 28 and an intermediate chamber 29 having an overflow pipe 30.

Any influx of water to the chamber 1 in 15 excess of its capacity will be forced through the restricted opening 31 into the chamber 28. Whenever any such influx of water to the chamber 1 is produced by the short pulsation of the water hammer, a small amount 20 of water will be forced into the chamber 28 and as soon as the pressure in the chamber 1 is relieved the diaphragm 25 and plug 26 will be forced down by a spring 32, allowing the water accumulated in the chamber 25 28 to flow through the opening 27 into the intermediate chamber 29 and escape through the pipe 30. If, however, the reduction in pressure in the annular space 16 is continued, as would occur by the release of the 30 sprinkler head 20, the flow of water into the chamber 1 will be continued until the chamber 28 fills and sets in operation an alarm of any suitable construction, consisting, in the present instance, of a small wheel 35 closed in a case 33 and operated by the flow of water through a pipe 34 to sound a gong 35.

That part of my apparatus which 40 comprises the chambers 1, 28 and 29, with connected alarm devices, forms no part of my present invention. My present invention relates to that portion of the device connected with the water supply pipe by which the 45 flow of water through the pipe 2 to any desirable alarm operating device may be controlled by means of a differential diaphragm.

The differential diaphragm, according to 50 my invention, has one side exposed to the direct pressure of water in the supply pipe and the other side exposed to a water pressure which is determined by the variation in the lateral pressure of a stream of water under motion through a contracted space.

55 I claim,

1. In an apparatus for operating alarms, a main pipe communicating with a source of water under pressure and provided with an opening in one of its sides, a chamber supported on the side of said main pipe and divided into an outer and an inner section by a diaphragm, the inner section communicating with said main pipe through said opening, a water pressure chamber, a pipe

connecting said inner section of the dia- 65 phragm chamber with the water pressure chamber and arranged to contact normally with the diaphragm to be closed thereby, and means for varying the pressure in said outer section of the diaphragm chamber by 70 the flow of water through said main pipe.

2. In an apparatus for operating alarms, and comprising a water pressure chamber, the combination of a main supply pipe, means for reducing the water pressure in 75 an annular section of said supply pipe by the flow of water through the pipe, a chamber supported on the side of said supply pipe, a diaphragm inclosed in said chamber, the space at the side of the diaphragm next 80 the supply pipe being in communication therewith, a pipe connecting said supply pipe and the water pressure chamber arranged to be normally closed by the contact of the diaphragm, and a pipe connecting 85 said annular water space in the supply pipe with said diaphragm chamber on the side of the diaphragm opposite said supply pipe.

3. In an apparatus for operating alarms, a supply pipe having oppositely tapered 90 passages and an annular water space at the smaller ends of said tapering passages and communicating therewith, a diaphragm chamber supported at the side of said supply pipe, a diaphragm inclosed in said 95 chamber, there being communication between one side of the diaphragm chamber and the supply pipe, a water pressure chamber, means for connecting the other side of the diaphragm chamber with said annular 100 water space, and a pipe leading from the side of said diaphragm chamber next to the supply pipe to the water pressure chamber, arranged to be normally closed by the contact of the diaphragm with the end of said 105 pipe.

4. In an apparatus for operating alarms, the combination with a main pipe having oppositely tapering passages and an annular water space at the smaller ends of said 110 passages and communicating therewith, a diaphragm chamber, a diaphragm inclosed in said chamber, a water pressure chamber, a pipe communicating with the water passage in said main pipe and leading to the water 115 pressure chamber, with its entrance end normally closed by the contact of said diaphragm, and a second pipe connecting the opposite side of said diaphragm chamber with said annular water space. 120

5. In an apparatus for operating alarms, a main water supply pipe having a contracted portion surrounded by and in communication with an annular space, a diaphragm chamber divided into two sections by a 125 diaphragm, one of the sections of the diaphragm chamber being in communication with the main supply pipe, a water pressure

chamber, a pipe connecting the water pressure chamber with the section of the dia-
phragm chamber next the main supply pipe
and arranged to be opened and closed by
5 movements of the diaphragm, and a pipe
connecting the annular space surrounding
the contracted portion of the main supply

pipe with the other section of the dia-
phragm chamber.
